UNITED STATES PATENT OFFICE.

CHARLES A. BALS, OF CHICAGO, ILLINOIS, ASSIGNOR TO CORWIN TELEPHONE
MANUFACTURING COMPANY, A CORPORATION OF ILLINOIS.

TELEPHONY.

1,040,635.

Specification of Letters Patent.

Patented Oct. 8, 1912.

Application filed May 22, 1911. Serial No. 628,749.

To all whom it may concern:

Be it known that I, CHARLES A. BALS, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to that class of telephone exchange systems in which telephone lines are automatically extended at the exchange and my invention broadly contemplates such a telephone exchange system whether the extensions terminate at called telephone stations or are mere links between calling and called telephone lines.

My invention relates particularly to the switching mechanism that is employed at the telephone stations for operating the selecting mechanism at the exchange for automatically extending telephone lines.

My invention has for its object the provision of a construction whereby the operating portion of the switching mechanism may be formed in an individual unit, said unit being separably associated with the circuit that it is to control. The operating unit of the switching mechanism is provided with terminals for separably including the switching mechanism in the circuit that it is to control, these terminals having contacts that are mounted independently of the aforesaid terminals whereby the switching mechanism including these latter terminals may be removed without disturbing the connections of the circuit conductors leading to said contacts.

In the preferred embodiment of the invention, the terminals are in the form of leaf springs which are carried by the framework that supports the switching mechanism. The contacts are desirably in the form of screws against which the spring terminals are pressed when the switching mechanism is put in position, these contacts being mounted upon a framework or casing upon which the switching mechanism is removably secured.

I will explain my invention more fully by reference to the accompanying drawings showing the preferred embodiment thereof as employed in connection with a subscriber's desk stand that enters into a common

form of automatic telephone exchange system and which desk stand is equipped with the features of my invention.

In the drawings Figure 1 is a side elevation of a desk stand equipped in accordance with the preferred embodiment of the invention; Fig. 2 is a front elevation of the structure shown in Fig. 1; Fig. 3 is a view in elevation showing the apparatus of my invention, the lower portion of the desk stand casing, framework, or mounting that carries this apparatus being shown in section; Fig. 4 is a bottom view of the structure shown in Fig. 3; Fig. 5 is a diagrammatic view showing the circuit connections that are effected by the equipment illustrated in the other figures.

Like parts are indicated by similar characters of reference throughout all of the views.

The side 1 of a telephone line is connected with a contact screw 2 that is carried upon a mounting plate 3, this mounting plate being desirably removably secured to a main mounting 4 that, in the embodiment of the invention illustrated, is constituted of the base of the desk stand. There is an inner baselike structure 5 that is removably secured to the desk stand by an upward extension 6 screwed to the cylindrical portion 7 of the desk stand by fastening screws 8, though other means may be employed for uniting the inner base 5 with the stem 7 of the desk stand and with the main mounting 4 through the intermediation of said stem. The mounting plate 3 is removably secured to the element 5 by means of spring clips 3¹. The other side 9 of the telephone line is diagrammatically illustrated in Fig. 5 as being connected with the telephone receiver switch hook 10, the normal contact of this switch hook constituting one terminal of the bridge conductor whose other terminal is permanently connected with the side 1 of the line and which bridge conductor includes a signal receiver 11 and a condenser 12. The alternate contact 13 of the switch hook is connected with a screw contact 14 similar in mechanical construction to the screw contact 2 and similarly mounted upon the mounting plate 3. The alternate contact 15 of the switch hook is connected through the telephone receiver 16 and the telephone transmitter 17 with a contact screw 18 similar in mechanical construction to the con-

tacts 2 and 14 and similarly mounted in the mounting plate 3.

The switching mechanism for modifying the line circuit in order to set the selecting mechanism at the exchange into operation includes spring contacts 19, 20, and 21 that are adapted for engagement with the screw contacts 2, 14 and 18 respectively. The spring contact 19 is connected with a circuit opening and closing spring 22 provided with a contact 23 that it normally engages and which contact 23 is connected with the spring contact 21. When that switching mechanism which is employed at the substation for operating the selecting mechanism is idle, circuit between the line sides 1 and 9 is completed through the telephone receiver 16, when this receiver is removed from its switch hook, by way of a bridge connection which may be traced from the side 1 through the screw contact 2, the spring contact 19, the circuit opening and closing contacts 22 and 23, the spring contact 21, the screw contact 18, the transmitter 17, the receiver 16, the terminal contact of the receiver that is then engaged with the switch hook 10, said switch hook 10 to the side 9. When the selecting mechanism is to be operated, the bridge conductor between the sides 30 of the telephone line is interrupted at 22, 23, it being usual to shunt out the receiver and transmitter when circuit interruption occurs at 22, 23 to avoid objectionable noise in the telephone receiver 16. This result is accomplished by providing the additional elements 13, 14 and 20 which have been described and also the normally open shunt switch contacts 24 and 25, these latter contacts being closed during the circuit interrupting operation by mechanism which is well understood, the shunt about the receiver and transmitter then established being traceable from the contact 21, through the contacts 24 and 25 that are engaged during the dialing operation, the contacts 14 and 20, the contact 13 to the switch hook 10. The element which is employed for bringing contacts 24 and 25 together is diagrammatically illustrated at 26 but inasmuch as the mechanism by which this element 26 is operated is so well known I will not describe its operation. The mechanism that interrupts the bridge conductor at 22 and 23 includes a cam 27 that engages the contact 23 to move it from its companion 22 to open the bridge conductor and to permit the contact 23, by its own resilience, to move toward the contact 22 to engage it and thereby close the bridge conductor. This cam is operated by means of dial mechanism 28 which is so very well understood as to render a description thereof superfluous. The dial mechanism 28, the cam 27, the spring contacts 19, 20 and 21, the bridge making and breaking contacts 22 and 23, the telephone

receiver and transmitter shunting contacts 24 and 25, and the element 26 that establishes the shunt connection at 24 and 25 when dialing is taking place are all provided upon a framework or mounting that includes a bottom plate 29, a top plate 30 and posts or struts 31 that constitute distance preserving devices for maintaining the plates 29 and 30 in proper relation. These posts 31 also serve as anchorage means whereby the base 4 and the mounting for the parts 19 to 26 inclusive which have just been described may be separably secured together. I prefer separably to secure the base 4 and the mounting for the parts 19 to 26 inclusive in position by means of screws 32 that pass through the cylindrical projection 33 of the base 4 and into the posts 31.

The line sides 1 and 9 of the telephone line may be associated with the contacts 2, 14 and 18 in a way that is mechanically independent of the wiring that associates the parts 19 to 25 inclusive, these latter parts being electrically associated and mechanically supported by a mounting that is structurally distinct from the mounting 4 that carries the contacts 2, 14 and 18, these two mountings being separably united in a manner to permit of the proper electrical association of the contacts carried thereby when the equipment is assembled.

The switching mechanism that is carried by the mounting structure that is mainly composed of the parts 29, 30 and 31 is, in the embodiment of the invention illustrated, controlled by the dial mechanism that so commonly enters into the equipment that is supplied by the Automatic Telephone Company of Chicago, Illinois. I do not wish to be limited, however, to the mechanism by which the circuit interrupting switch is operated.

Having thus described my invention I claim as new and desire to secure by Letters Patent the following:

1. Apparatus for automatically effecting extension of telephone lines which includes switching mechanism for governing the circuit of the selecting mechanism that is to effect the line extension; engaging contacts for establishing the circuit relation of said switching mechanism, these contacts being carried by separably engaged mountings, the switching mechanism being carried by one of said mountings; and a mounting plate for the contact carried by the other mounting separably secured to said other mounting a contact carried by the mounting plate having a line conductor connected therewith which is bodily movable with the contact and the mounting plate for the contact.

2. Apparatus for automatically effecting extension of telephone lines which includes switching mechanism for governing the circuit of the selecting mechanism that is to

effect the line extension; engaging contacts for establishing the circuit relation of said switching mechanism and one of which is a spring contact, these contacts being carried by separably engaged mountings, the switching mechanism being carried by one of said mountings; and a mounting plate for the contact carried by the other mounting separably secured to said other mounting a contact carried by the mounting plate having a

line conductor connected therewith which is bodily movable with the contact and the mounting plate for the contact.

In witness whereof, I hereunto subscribe my name this sixteenth day of May A. D., 1911.

CHARLES A. BALS.
